CONVERSION OF HYDROCARBON OILS

Kenneth Swartwood, Chicago, Ill., assignor to
Universal Oil Products Company, Chicago, Ill.,
a corporation of Delaware

Application May 23, 1934, Serial No. 727,068

2 Claims. (Cl. 196—49)

This invention particularly refers to an improved process for the fractional distillation of hydrocarbon oils of relatively wide boiling range, accompanied by the pyrolytic conversion of selected fractions of the oil employing a plurality of successive conversion stages, each of which is devoted to the separate conversion of selected low-boiling and high-boiling fractions of the intermediate products of the preceding stage, the intermediate products of the final cracking stage being either withdrawn, all or in part, from the system or returned, all or in part, to further conversion in any desired preceding stage of the system.

The advantages of selective cracking, i. e. conversion of selected fractions of oils of different boiling characteristics each under independently controlled conversion conditions, are now well recognized. It has proven advantageous in processes operated primarily for the production of low-boiling products, such as motor fuel of high antiknock value, from the standpoint of both the yield and quality of the final light distillate product. This is generally accounted for by the fact that oils of materially different boiling characteristics require different cracking conditions for their most advantageous treatment and that higher yields of the desired products may be obtained from a given oil of relatively narrow boiling range under the cracking conditions to which it is best suited when unmixed with any appreciable quantity of substantially lower boiling or higher boiling oils.

In cracking operations employing the recirculation of intermediate conversion products (reflux condensate formed in the fractionator of the system) to the heating coil for further conversion the ratio of the quantity of reflux condensate returned to the heating coil to the quantity of raw oil charging stock supplied to the system, when cracking an oil of relatively wide boiling range is normally from 3:1 to 5:1 and in some cases even more. This means that reflux condensate formed by conversion of the charging stock during its initial passage through the heating coil is subjected to further conversion not only with the charging stock but also with reflux condensates formed by further conversion of the previously formed reflux condensate and indicates that some portions of the reflux condensate are recycled through the heating coil and subjected to further conversion several times while other portions of the reflux condensate are subjected to further conversion only once.

I have found that, when a cracking process is

divided into several successive conversion stages, each maintained under independently controlled conversion conditions and each stage, after the first, being devoted to the further conversion of intermediate products (reflux condensate) from the preceding stage, a higher yield and better quality of product may be obtained. I have applied the term "stage cracking" to this method of operation and in the present invention, in order to obtain the advantages of both stage cracking and selected cracking, the charging stock, as well as the intermediate conversion products of each cracking stage are separated into selected low-boiling and high-boiling fractions each of which are subjected to independently controlled conversion conditions in the succeeding stage of the cracking operation.

It is, of course, apparent that there is an economic balance between the number of different cracking stages which may be employed as well as the degree of selectivity of the operation (the number of selected fractions into which the charging stock and intermediate conversion products of each stage are separated) and the improved results obtainable. It is, therefore, not intended to limit the invention to any specific number of cracking stages or to any specific degree of selectivity and, in the preferred form of the present invention, the intermediate conversion products of the final cracking stage of the process may be removed, all or in part from the system, or may be returned, all or in part, to that stage of the system employing the conditions most suitable for their further conversion and, particularly, in the latter case, are preferably separated into selected low-boiling and high-boiling fractions each of which are subjected to independently controlled conversion conditions in the particular stage to which each is returned.

In one specific embodiment, the invention comprises subjecting hydrocarbon oil of relatively wide boiling range to fractional distillation whereby it is separated into low-boiling, intermediate and high-boiling components, separately recovering the low-boiling and high-boiling components, separating the intermediate components into selected low-boiling and high-boiling fractions, subjecting each of said fractions to independently controlled conversion conditions of elevated temperature and superatmospheric pressure, commingling the resulting products, separating the commingled materials into low-boiling, intermediate and high-boiling components, separately recovering the last mentioned low-boiling and high-boiling components, sepa- 55

rating the last mentioned intermediate components into selected low-boiling and high-boiling fractions, subjecting each of the last mentioned selected fractions to independently controlled 5 conversion conditions of elevated temperature and superatmospheric pressure, commingling the resulting products, separating the last mentioned commingled materials to low-boiling, intermediate and high-boiling components, separately re- 10 covering the last mentioned low-boiling and high-boiling components, separating the last mentioned intermediate components into selected low-boiling and high-boiling fractions and subjecting each to further conversion in a selected 15 preceding conversion stage of the system.

The accompanying diagrammatic drawing illustrates one specific form of apparatus in which the process may be practiced. Referring to the drawing, raw oil charging stock for the 20 process, comprising hydrocarbon oil of any desired type, particularly oils of relatively wide boiling range and specifically including oil such as crude petroleum containing an appreciable quantity of materials within the boiling range of gaso- 25 line, is supplied through line 1 and valve 2 to pump 3 by means of which it is fed through line 4, valve 5, heating coil 6, line 7 and valve 8 into distilling and fractionating column 9.

Heating coil 6 is located within a furnace 10 of any suitable form by means of which sufficient heat is supplied to the charging stock to effect its substantial subsequent vaporization in column 9. Any desired pressure ranging from substantially atmospheric to several hundred pounds per sq. 30 in. may be employed in heating coil 6 and, when desired, particularly in case the charging stock is an oil of relatively narrow boiling range the temperature employed within the heating coil may be sufficient to effect its pyrolytic conver- 35 sion. Preferably, however, in case the charging stock is of relatively wide boiling range only mild conversion temperatures or a temperature below that at which any appreciable conversion of the charging stock will occur under the pressure con- 40 ditions prevailing in this zone, are employed therein.

The heated materials supplied, as described, to column 9 are separated therein by fractional distillation into low-boiling, intermediate and high- 50 boiling fractions. The high-boiling fractions are allowed to accumulate within the lower portion of column 9 and, in the case here illustrated, are withdrawn therefrom through line 11 and valve 12 to cooling and storage or to any desired fur- 55 ther treatment. This material may comprise, for example, heavy fuel oil, or, in general high-boiling components of the charging stock or of the conversion products, in case conversion temperatures are employed in heating coil 6, which it is 60 not desired to subject to further conversion.

Fractionated vapors of the desired end-boiling point, comprising any low-boiling components of the charging stock or conversion products, in case cracking conditions are employed in heating coil 65 6, which it is not desired to subject to further conversion, such as, for example, materials within the boiling range of motor fuel, may be withdrawn, together with uncondensable gas, from the upper portion of column 9, through line 13 70 and valve 14 to be subjected to condensation and cooling in condenser 15. The resulting distillate and gas passes through line 16 and valve 17 to collection and separation in receiver 18. Uncondensable gas may be released from the re- 75 ceiver through line 19 and valve 20. Distillate

may be withdrawn from receiver 18 through line 21 and valve 22 to storage or to any desired further treatment.

The intermediate components of the materials supplied to column 9, comprising materials which it is desired to subject to further conversion within the system, are separated by fractionation in column 9 into selective low-boiling and high-boiling fractions. The high-boiling fractions may be withdrawn from any desired intermediate 5 point or plurality of points in column 9, such as, for example, through line 23 and valve 24, to pump 25, by means of which they are supplied through line 26 and valve 27 to conversion in heating coil 28. The low-boiling fractions of the 10 intermediate components from column 9 are separately withdrawn from any suitable intermediate 15 point or plurality of points in the column, for example, through line 29 and valve 30, to pump 31, by means of which they are supplied through line 32 and valve 33 to conversion in heating coil 34.

Heating coils 28 and 34 are located within the respective furnaces 35 and 36, each of any desired form, by means of which the respective 25 high-boiling and low-boiling fractions are each subjected to independently controlled conversion temperatures, preferably under independently controlled superatmospheric pressures. The heated products are discharged from heating coil 30 28 through line 37 and valve 38 and, in the case here illustrated, commingle in line 39 with the stream of heated products discharged from heating coil 34 through line 39 and valve 40, the com- 35 mingled materials being discharged into column 41.

The conversion products supplied to column 41 are separated therein into desirable low-boiling, selected intermediate and high-boiling components. The latter, comprising residual liquid conversion products, may be withdrawn from the lower portion of the column through line 42 and valve 43 to cooling and storage or to any desired further treatment. The desirable low-boiling components are withdrawn as fractionated vapors 45 of the desired end-boiling point from the upper portion of column 41, together with uncondensable gas, through line 44 and valve 45 to be subjected to condensation and cooling in condenser 46. The resulting distillate and gas passes 50 through line 47 and valve 48 to collection and separation in receiver 49. Uncondensable gas may be released from the receiver through line 50 and valve 51. Distillate may be withdrawn from the receiver through line 52 and valve 53 to 55 storage or to any desired further treatment. Components of the vapors undergoing fractionation in column 41 boiling above the range of the desired final light distillate product from this stage of the process are condensed in column 41 60 as reflux condensate and separated by fractionation into selected low-boiling and high-boiling fractions.

The high-boiling fractions of the reflux condensate are withdrawn from a suitable point in column 41 above the point of introduction of the hot conversion products, for example, through line 54 and valve 55, to pump 56 by means of which they are supplied through line 57, valve 58 and line 59 to further conversion in heating 70 coil 60. Low-boiling fractions of the reflux condensate formed in column 41 are withdrawn from any suitable intermediate point or plurality of points in this zone, for example, through line 61 and valve 62, to pump 63 by means of which they 75

are supplied through line 64, valve 65 and line 66 to further conversion in heating coil 67.

Heating coils 60 and 67 are located within the respective furnaces 68 and 69, each of any desired form, by means of which the respective high-boiling and low-boiling fractions of the reflux condensate from column 41 are each subjected to independently controlled conversion conditions of elevated temperatures and super-atmospheric pressures. The highly heated products are discharged from heating coil 67 through line 70 and valve 71, commingling, in the case illustrated, in line 72 with the stream of heated products discharged from heating coil 60 through line 72 and valve 73, the commingled materials being discharged into column 74.

Conversion products supplied to column 74, as described, are separated into desirable low-boiling, selected intermediate and high-boiling fractions. The latter comprising residual liquid conversion products, may be withdrawn from the lower portion of column 74 through line 75 and valve 76 to cooling and storage or to any desired further treatment. The low-boiling fractions, comprising components of the conversion products boiling within the range of the desired light distillate product of this stage of the process, are withdrawn as fractionated vapors from the upper portion of column 74, together with uncondensable gas, through line 77 and valve 78 to be subjected to condensation and cooling in condenser 79. The resulting distillate and gas passes through line 80 and valve 81 to collection and separation in receiver 82. Uncondensable gas may be released from the receiver through line 83 and valve 84. Distillate may be withdrawn from receiver 82 through line 85 and valve 86 to storage or to any desired further treatment. Intermediate fractions of the conversion products supplied to column 74 comprising vaporous products boiling above the range of the desired final light distillate product of this stage of the system are condensed by fractionation in this zone and are separated into selected low-boiling and high-boiling fractions.

High-boiling fractions of the reflux condensate from column 74 may be withdrawn from any suitable point in this zone above the point of introduction of the hot conversion products, for example, through line 87 and valve 88, to pump 89 by means of which they are fed through line 90 and may be returned, all or in part, either through valve 91 and line 59 to further conversion in heating coil 60, together with the high-boiling fractions of the reflux condensate from column 41, or through line 92, valve 93 and line 26 to further conversion in heating coil 28, together with the high-boiling fractions of the reflux condensate from column 9.

Low-boiling fractions of the reflux condensate formed in column 74 may be withdrawn from any suitable intermediate point or plurality of points in this zone, for example, through line 94 and valve 95, to pump 96 by means of which they are fed through line 97 and may be directed, all or in part, through valve 98 and line 66 to further conversion in heating coil 67, together with low-boiling fractions of the reflux condensate from column 41, or through line 99, valve 100 and line 32 to further conversion in heating coil 34, together with low-boiling fractions of the reflux condensate from column 9.

In a process such as illustrated and above described, the preferred range of operating conditions may be approximately as follows; the heat-

ing coil to which raw oil charging stock for the process is supplied may utilize an outlet temperature within the range of relatively mild conversion conditions or, may employ a temperature when desired, below that at which any appreciable conversion of the oil will occur; the preferred temperatures ranging, for example, from 600 to 900° F., or thereabouts, with any desired pressure measured at the outlet from the heating coil within the range of substantially atmospheric pressure to 300 pounds, or more, per sq. in. The pressure employed in the succeeding distilling and fractionating column may be substantially equalized or appreciably reduced relative to the pressure employed at the outlet from the heating coil. The temperature employed at the outlet from the heating coil to which high-boiling fractions of the reflux condensate from the first distilling and fractionating column are supplied may range, for example, from 800 to 900° F., or thereabouts, preferably with a substantial superatmospheric pressure measured at this point in the system of from 100 to 500 pounds, or thereabouts, per sq. in. The temperature employed at the outlet from the other heating coil of this stage of the process, to which low-boiling fractions of the reflux condensate from the first distilling and fractionating column are supplied, may range, for example, from 900 to 1000° F., or thereabouts, preferably with a superatmospheric pressure at the outlet from the heating coil of from 200 to 800 pounds, or more, per sq. in. The pressure employed in the succeeding fractionating and distilling column may be either substantially equalized with or appreciably reduced relative to the pressure employed in the preceding heating coil employing the lowest pressure. The temperature employed for conversion of the high-boiling fractions of the reflux condensate from the second distilling and fractionating column, as measured at the outlet from the heating coil may be within the range of 850 to 950° F., preferably with a superatmospheric pressure at this point in the system of from 100 to 500 pounds, or thereabouts, per sq. in.

The temperature employed at the outlet from the heating coil to which low-boiling fractions of the reflux condensate from the second distilling and fractionating column are supplied may range, for example, from 950 to 1050° F., preferably with a superatmospheric pressure of from 200 to 800 pounds, or more, per sq. in. The succeeding fractionating and distilling column may utilize a pressure either substantially equalized with or somewhat reduced relative to that employed at the outlet from the preceding heating coil utilizing the lowest pressure. The condensing and collecting equipment of each stage of the process may utilize pressures substantially the same or somewhat reduced relative to the pressure employed in the communicating distilling and fractionating column.

As a specific example of one of the many possible operations of the process of the present invention as it may be practiced in an apparatus such as illustrated and above described, the charging stock, comprising a Kansas crude of about 36° A. P. I. gravity, is subjected in the first heating coil to an outlet conversion temperature of approximately 650° F. at a superatmospheric pressure of about 150 pounds per sq. in. Low-boiling fractions of the straight-run gasoline contained in the crude, boiling up to approximately 350° F. and comprising a little less than 20 percent of the charging stock, are collected

as the light distillate product from the first distilling and fractionating column and asphaltic residue comprising approximately 25 percent of the charging stock separately recovered as the bottoms from the first distilling and fractionating column. The intermediate components of the charging stock are separated into fractions boiling above and below approximately 550° F. The low-boiling materials are subjected in a 5 separate heating coil to an outlet conversion temperature of approximately 970° F. at a superatmospheric pressure of about 800 pounds per sq. in. The high-boiling fractions are subjected in another separate heating coil to an 10 outlet conversion temperature of approximately 920° F. at a superatmospheric pressure of about 300 pounds per sq. in. The heated materials are commingled and introduced into the second distilling and fractionating column which is operated at a superatmospheric pressure of about 15 15 150 pounds per sq. in. The light distillate product of this stage of the process comprises motor fuel having an end-boiling point of approximately 385° F. and the residual liquid recovered as bottoms from the distilling and fractionating column is suitable as fuel. The intermediate fractions (reflux condensate) are separated into selected low-boiling and high-boiling fractions, the former, having a boiling range of approximately 20 25 30 35 40 45 50 385 to 550° F., are subjected in a separate heating coil to an outlet conversion temperature of approximately 980° F. at a superatmospheric pressure of about 800 pounds per sq. in. The high-boiling fractions of the reflux condensate are separately subjected in another separate heating coil to an outlet conversion temperature of approximately 950° F. at a superatmospheric pressure of about 350 pounds per sq. in. The two streams of heated products in the last mentioned heating coils are commingled and the commingled materials are introduced into a separate distilling and fractionating column. The overhead distillate product from the last mentioned distilling and fractionating column comprises motor fuel having an end-boiling point of approximately 400° F. and the residual liquid withdrawn as bottoms from this zone is also a good quality fuel oil. The intermediate conversion products (reflux condensate) are separated into selected low-boiling and high-boiling fractions boiling respectively above and below approximately 550° F. which are returned, respectively, to the last mentioned high-temperature and low-temperature heating coils for further conversion.

This operation will produce, per barrel of charging stock, approximately 58.5 percent of motor fuel, the blended product from all three stages of the process (including the straight-run gasoline) having an antiknock value equivalent to an octane number of approximately 65 and in addition there may be produced about 25 percent of asphaltic material and about 12 percent of good quality fuel oil, the remainder being chargeable principally to uncondensable gas.

I claim as my invention:

1. A hydrocarbon oil conversion process which comprises fractionating the charging oil and separating therefrom a relatively light cracking stock and a heavier cracking stock, subjecting said cracking stocks to separate independently controlled cracking treatments and then combining resultant conversion products, fractionating the commingled vapors and separating therefrom a relatively light reflux condensate and a heavier reflux condensate, cracking these condensates independently of each other and independently of said cracking stocks, subjecting the cracked vapors of said condensates to common fractionation and separating from these commingled vapors a relatively light recycle stock and a heavier recycle stock, retreating said light and heavier recycle stocks together with said light and heavier cracking stocks respectively, and finally condensing the fractionated vapors.

2. A hydrocarbon oil conversion process which comprises fractionating the charging oil and separating therefrom a relatively light cracking stock and a heavier cracking stock, subjecting said cracking stocks to separate independently controlled cracking treatments and then combining resultant conversion products, fractionating the commingled vapors and separating therefrom a relatively light reflux condensate and a heavier reflux condensate, cracking these condensates independently of each other and independently of said cracking stocks, subjecting the cracked vapors of said condensates to common fractionation and separating from these commingled vapors a relatively light recycle stock and a heavier recycle stock, retreating said light recycle stock in part with said light cracking stock and in part with said light reflux condensate, retreating said heavier recycle stock in part with said heavier cracking stock and in part with said heavier reflux condensate, and finally condensing the fractionated vapors.

KENNETH SWARTWOOD.
